Patterson

Application October 9, 1944, Serial No. 557,870

17 Claims. (Cl. 74—41)

1

This invention relates to counterbalanced well pumping mechanism, and particularly pertains to a method and means for pumping air in air balanced pumping units.

In pumping units, such for example as well pumping units in which a walking beam operates a string of pump rods, it is necessary to provide means for counterbalancing the apparatus to compensate for variation in load upon the opposite strokes of the pump mechanism. In some instances a counterbalance weight is provided for this purpose, while in other instances a fluid counterbalance is provided, such as disclosed in U. S. Patent No. 2,293,915 issued August 25, 1942, to Edgar W. Patterson. In such apparatus it is desirable to provide means for pumping air into the fluid counterbalance system and into the main air tank forming a part of the air-balanced pumping unit. In the type of pumping equipment disclosed in the aforementioned patent a main balance cylinder of the double acting type is employed, the upper portion of which cylinder can be utilized for the purpose of supercharging an air compressor constantly while the pumping unit is in normal operation by simply connecting a suitable pipe between the intake of the compressor and the discharge from the compressor portion of the balance cylinder. Therefore, this connection may be arranged to discharge air directly into the main operating compressor cylinder of an air-balanced pumping unit. This method of supercharging the compressor constantly would not require the use of any small air receiver because the compression of air above the piston within a double acting counterbalance cylinder would take place synchronously with the up-stroke or intake stroke of any reciprocating compressor which might be operated from the oscillation of a walking beam, such as is disclosed in U. S. Patent No. 2,293,916 issued August 25, 1942, to Edgar W. Patterson. Attention is also directed to the general type of air compressor shown in U. S. Patent Reissue No. 20,287 issued to Edgar W. Patterson on March 9, 1937, and in which structure it would not be necessary to employ an auxiliary air receiver in the event a constant discharge air compressor is used and would make no particular difference whether the counterbalance cylinder was either double or single-acting, except that in case a single-acting counterbalance cylinder is used the air compressor could only be supercharged while the main control valve is closed and at which time the pumping

2

unit would not be functioning in normal operation.

The foregoing specific example of a method and means for supercharging an air compressor constantly or intermittently in a counterbalancing system have been made to emphasize the desirability of providing simple means for supercharging the compression system without the use of an auxiliary compressor.

10 It is desirable to provide means manually and optionally controlled for introducing atmospheric air into the counterbalance system of a pumping unit, and when desired to be able to supercharge the main operating air compressor which furnishes air under pressure to the unit.

15 It is the principal object of the present invention, therefore, to provide a method and means of constantly pumping air into the fluid counterbalance system of a pumping unit incident to the pumping operation by the use of simple apparatus which may be controlled by manual operation to supercharge the air compressor and to maintain a desired uniform degree of fluid pressure within the system completely under the control of the operator.

20 The present invention contemplates a pumping unit, including a pneumatic counterbalance which may employ a single or double-acting balancing cylinder operating in conjunction with an auxiliary compressor by a method whereby the unit may be manually controlled to supercharge the compressor and to continuously supply air to the system for counterbalancing purposes, at a substantially constant pressure value.

25 The invention is illustrated by way of example in the accompanying drawings in which:

Figure 1 is a view in side elevation showing the structure of Fig. 2 and the apparatus with which the present invention is concerned and indicating the relation of parts of the counterbalancing apparatus and compressor.

30 Fig. 2 is a view in end elevation showing a pump mechanism and indicating generally the construction and arrangement of the counterbalancing cylinder and one form of the present invention.

35 Fig. 3 is an enlarged view in vertical section and elevation with parts broken away showing a double-acting compressor cylinder and an alternate arrangement of piping connections thereto, and indicating the piping in a common transverse plane for sake of convenience.

40 Fig. 4 is a view in side elevation showing the structure of Fig. 3 and the compression cylinder with the fluid circulating conduits connected

3

therewith, the conduits in this view differing in location from those shown in Fig. 3 only in that they are here indicated at ninety degrees to each other.

Fig. 5 is an enlarged view in vertical section and elevation showing a conventional type of single-acting air compressor which may be employed in practising the present method.

Fig. 6 is a view in transverse section showing the air compressor disclosed in Fig. 5 and indicating particularly the valve and pipe connections thereto.

Referring more particularly to Figs. 1 and 2 of the drawings, 10 indicates a base structure which is here shown as made from suitable structural steel elements. Rigidly secured to the upper face of the base structure and near one end thereof is a pair of structural elements forming a samson post 11. A king pin 12 is carried at the upper end of the samson post 11 and pivotally supports a walking beam 13. The walking beam is vertically reciprocated by a driving unit 14 which carries a crank disc 15. The discs 15 are fitted with crank pins 16 engaging the lower ends of pitman rods 17. The upper ends of pitman rods 17 are pivoted to the walking beam 13 at a point intermediate its ends upon a pin 18. The oscillation of the walking beam 13 is counterbalanced by a balance cylinder 19 within which a piston 20 reciprocates. The upper end of the balance cylinder 19 is pivoted to the walking beam upon a pin 21 disposed between the pitman rod pin 18 and the free end of the walking beam. The balance cylinder 19 is closed at its upper end and may be open at its lower end, as shown in Fig. 2 of the drawings. The piston 20, which is mounted therein, is carried upon a tubular piston rod 22 through which communication is established with the compression chamber 23 in the head of the cylinder. The piston rod 22 extends downwardly and is connected to a transverse T-end 24 which is mounted in a pair of spaced bearing blocks 25 carried upon a base frame structure 26 which extends around an air reservoir 27. The air reservoir is in the form of a tank extending with its longitudinal axis horizontal, and is here indicated as having its axis in the vertical plane of the axis of the balance cylinder 19. The T-shaped fitting 24 at the lower end of the piston rod has a passageway through one leg thereof communicating with a passageway 22', which extends within and longitudinally of the piston 22. The passageway in the member 24 is provided with a pipe connection 28 which extends horizontally and connects at its outer end with a T-pipe fitting 29. One horizontal leg of the T-fitting 29 connects with an intake check valve 30. The other horizontal leg connects with a discharge check valve 31. A vertical leg of the T-fitting 29 connects with a main air control valve 32 which is designed to be operated manually. A pipe 33 is connected to the valve 32 and extends downwardly to engage the vertical leg of a T-fitting 34. One horizontal leg of the T-fitting 34 is provided with a pipe 35 which establishes communication with the air reservoir 27. The other horizontal leg of the T-fitting 34 is provided with a check valve 36 which permits fluid to pass through the valve toward the T-fitting 34 and interrupts the flow of fluid in the opposite direction. A conduit 37 is connected to the opposite side of the check valve 36 and connects with a T-fitting 38. One leg of this fitting connects with a T-fitting 39 by means of a pipe 40. The T-fit-

4

ting 39 is connected to the check valve 31 by a pipe 41. The opposite leg of the T-fitting 39 is connected to a manually controlled valve 42 which opens to atmosphere.

The T-fitting 38 is provided with a conduit 43 connecting with a surge tank 44. The surge tank has a capacity several times greater than the capacity of the balance cylinder 19 so that air may be delivered to an air compressor at substantially constant pressure. At the opposite side of the point of connection of the conduit 43 with the surge tank 44 and near the bottom of the surge tank 44 is a pipe 45. This connects with a manually operable shut-off valve 46 which is attached to a pipe 47. The pipe 47 connects with a check valve 48 through which air may pass to a pipe 49 connected to the bottom of an auxiliary air compressor cylinder 50. This air compressor is of the single-acting type and is provided with a piston 51 connected to a pitman rod 52. The pitman rod 52 is connected pivotally to the walking beam 13 upon a pivot 53 which is disposed at a point between the king pin 12 and the pivot pin 18.

In the form of the invention shown in Fig. 3 of the drawings a double-acting balance cylinder 19' is provided with a pipe connection 54 receiving a T-fitting 55 to which a manually operated valve 56 is attached. A pipe 57 connects the T-fitting 55 to a T-fitting 58. One leg of the T-fitting 58 carries an intake check valve 59, and another leg of the fitting is connected to a manually operated valve 60. The valve 60, as shown in Figs. 3 and 4 of the drawings, is provided with a pipe 61 which connects with a secondary discharge check valve 62. The secondary discharge check valve 62 is fitted with a pipe 63 directly connecting with the balance cylinder 19' at a point below the lower end of the stroke of piston 20'. In the particular form of invention shown in Fig. 3 it will be noted that the cylinder and piston are inverted so that piston rod 22'' extends upwardly and is connected to the walking beam 13 while the cylinder 19' is pivotally mounted within the bearing blocks 25 and is fitted with the outlet connection 28 previously described. The remaining construction of the compressor and circulating system of the structure in Fig. 3 is the same as that shown in Fig. 1 of the drawings, with the exception that a manually operated cut-off valve 64 is interposed in the length of the conduit 43 which connects the T-fitting 38 with the surge tank 44, as shown in Fig. 4 of the drawings. It will also be noted by an examination of this figure of the drawings that the manually operated valve 46, which had been shown in Fig. 1 as interposed between the pipes 45 and 47, has been eliminated and a conduit 65 has been provided to establish a connection with the check valve 48.

By reference to Figs. 3 and 4, it will be seen that the upper end of the cylinder 19' is fitted with an outlet pipe 66 which connects with a check valve 67. The check valve 67 allows air to pass from the cylinder 19' but not to enter the cylinder through the pipe 66. A pipe 68 is connected to the outside of the check valve and carries a manually operated cut-off valve 69. A pipe 70 is attached to the cut-off valve 69 and has a flexible conduit 70' secured to it. This conduit is connected with the upper end of the surge tank 44.

The auxiliary air compressor 50 is shown in Figs. 5 and 6 of the drawings. The compression head of the auxiliary air compressor 50 is pro-

5

vided with a pipe connection 71 which leads to a check valve 72. The check valve 72 is connected with a pipe 73 attached to the main air reservoir and a pressure indicating gauge 74. The valve 72 permits flow of fluid from the compressor 50 to the main air receiver and gauge. Also connected to the compression head of the auxiliary compressor 50 is a pipe 75. At the outer end of this pipe a check valve 76 is provided. The valve 76 permits the entry of air into the auxiliary compressor 50 and prevents a reverse flow of air therethrough.

At the present time the most useful application of the invention is by operating the single-acting auxiliary compressor 50, as is employed on most air-balanced units in synchronous operation with a reciprocating air-balance cylinder and compressor, such as indicated at 19, and by which arrangement the pumping rate of air into the main air receiver of a present-day type of air-balance pump unit will be greatly increased. It is to be understood in explaining the present invention that the combination of the valves shown in Fig. 1 of the drawing and there indicated by the numerals 36, 31, 32 and 33, and the conduits connecting them with the balance cylinder 19 and air receiver 27, involve a method of utilizing the balance cylinder 19 of an air-balance pump unit as a primary compressor for initially charging the main air receiver 27 of an air-balanced pumping unit with air under a pressure, which in all probability will be less than the maximum pressure required for ideal operation of the unit. This method and the specific structure used in practising it is shown and described in U. S. Patent No. 2,293,915 issued to Edgar W. Patterson on August 25, 1942, and also in connection with a single-acting balance cylinder shown and described in U. S. Patent No. 2,218,216 issued to Charles M. O'Leary on the 15th day of October, 1940.

The present invention is concerned with a method and means for greatly increasing the output capacity of any type of compressor as shown in patents mentioned hereinbefore, and accomplishes this by connecting the balance cylinder of either the double or single acting type with the intake of a compressor which is arranged to discharge air under pressure direct to the main air receiver 27 of the pumping unit. This result is accomplished while either the upper or lower compression spaces of the balance cylinder are being utilized as a compressor and not for counterbalancing purposes.

Before explaining the operation of the invention a thorough technical understanding of the advantages to be gained by the use of this construction is desirable. This may be had from an analysis of the mathematical formulae governing the isothermal compression of air or gases, wherein:

$$\frac{P_1 \times V_1}{P_2} = V_2$$

and wherein

P_1 =original absolute pressure in lbs.

V_1 =original volume in cubic inches

P_2 =second absolute pressure

V_2 =second volume

A typical example of an actual problem would be as follows:

Assume a pumping unit to be operating at 20 revolutions, or strokes, per minute while the process of pumping up air to say 200 pounds per square inch in the main air receiver is taking

6

place. Assume that a compressor of 5-inch diameter by 7-inch stroke is being used for the purpose. Therefore, the displacement in cubic inches per minute equals

$$5 \times 5 \times 0.7854 = 19.635 \times 7 \times 20 = 2749$$

cubic inches. Therefore

$$\frac{2749 \times 14.7}{214.7} = 188$$

10 cubic inches of air per minute being compressed from 0 gauge pressure (14.7 absolute pressure) to (214.7 lbs. absolute) or 200 lbs. gauge pressure. And by the same formula wherein we utilize the

15 balance cylinder as a primary compressor for supercharging the same compressor as cited above to say 100 lbs. per square inch, we have

$$\frac{2749 \times 114.7}{214.7} = 1468$$

20 cubic inches per minute of air compressed to 200 lbs. gauge pressure per square inch or 7.8 times as much air being compressed and discharged into the main air receiver as was formerly discharged by the same compressor where-

25 in this improved method was not employed. Therefore, it is perfectly obvious to anyone that if it required 2 hours to charge the main air receiver of a unit up to 200 lbs. by the old method, it would require but 15½ minutes to do the same 30 thing by the use of this improved method.

With reference to the accompanying drawings, the construction of the unit embodying the invention and the method of practising the invention may be explained as follows:

35 By reference first to Figs. 1 and 2, it will be assumed that the pumping unit is idle and that all air pressure in the unit is at zero. First, the unit is set in motion at the normal revolutions per minute and the main air control valve 32 is closed.

40 This will cause the main balance cylinder 19 to function automatically as a compressor by draw-

45 ing air into the unit through the intake valve 30 and to discharge this air on the succeeding down-stroke of the balance cylinder 19 through pipes 28, 35 and 37 and the check valves 31 and 36. The air then passes into the main air re-

50 ceiver 27 by way of the pipe 35. It should be pointed out that during this period air will be trapped in the small surge tank or receiver 44 after it passes through the check valve 31 and while it is prevented from escaping to the compressor for the time being by manually operated valve 46. This action will take place during

55 the same period and under the same pressure as the air then being discharged into the main receiving tank 27. By this method the air pressure in the main receiver 27 will be built up quickly to approximately 100 pounds pressure per square inch. It will not be possible to develop

60 a pressure greatly in excess of 100 pounds per square inch because the clearance volume or space remaining in the balance cylinder 19 when it has completed its down or compression stroke is not and cannot be reduced to a smaller volume

65 conveniently. Therefore, within a comparatively short period of operation the pressure within the main air receiver 27 will be equal to the maximum pressure being developed by the balance cylinder 19 while it is functioning as a compressor. Under this condition no more air will be dis-

70 charged into the main air receiver 27 and the air entrapped within the balance cylinder will be re-compressed on each down-stroke and ex-
75 panded during each up-stroke of the walking beam without being displaced.

During the entire operation the auxiliary compressor 50 will be functioning in the normal manner whereby it will be drawing in air at atmospheric pressure during the up-stroke of its piston through intake valve 76 and will discharge air during the down-stroke of the piston through its discharge valve 72 and the pipe 73. The pipe 73 communicates with the main air receiver 27 and thus delivers the discharged air from the auxiliary compressor 50 to the main air receiver. At this stage of the operation during which the converted balance cylinder 19 no longer discharges air directly to the main air receiver 27, it is necessary to depend upon the auxiliary compressor 50 to supply air to the receiving tank 27. This is done as the auxiliary compressor 50 operates in its normal manner to draw air into its cylinder through the check valve 76 and the pipe 75 and to discharge air therefrom through the check valve 72 and the pipes 71 and 73 connected therewith. This is a rather slow process as compared to one in which the valve 46 is manually opened. When this valve is opened air at a pressure of approximately 100 pounds per square inch, as developed by the converted balance cylinder 19, will flow freely to the auxiliary compressor 50 through pipe 47 and the intake check valve 48. When this arrangement of the valves is made the balance cylinder 19 and the compressor 50 have a compound compression action, thus increasing the output capacity of the main operating compressor 7.8 times the normal compression action obtained from the compressor 50 as demonstrated in the foregoing calculations. The desired pressure within the main air receiver 27 will thus be quickly increased, and when this pressure reaches the estimated desired operating pressure for the unit the valve 46 should be closed again and the main air valve 32 should be opened. The unit is then considered to be ready for pumping operations and the pump rod of the well may then be connected to the walking beam so that normal operations can be started.

It will be apparent that the only added equipment required to bring about the increased efficiency in operation of the air compressor unit previously described consists principally of the following parts: check valve 31, pipe 45, surge tank 44, pipe 47, valve 46, and the check valve 48 and the auxiliary compressor 50. When a double-acting balance cylinder 19' is used the surge tank 44 may be eliminated. The type of double-acting balance cylinder 19' as shown in Fig. 3 of the drawing is one type in which it would not be necessary to use a surge tank 44 because the intake stroke of the auxiliary compressor 50 is in synchronism with the discharge stroke of the balance cylinder 19'.

In operation of the form of the device shown in Figs. 3 and 4 several alternate actions can be produced, for example by leaving valve 60 open, and valves 69 and 32 closed, the lower portion of the balance cylinder 19' will be supercharged by air under pressure as it is forced into the lower chamber during the up-stroke of the piston 29'. This air will then be forced under pressure into the surge tank 44 on the down-stroke of the piston 29' in the balance cylinder 19'. This action takes place precisely in the same manner as described in connection with the preferred form of the invention shown in Fig. 1.

When the valves are arranged so that valves 60 and 32 are closed and valve 69 is open, then the air compressor may take air under pressure directly from the compression space within cyl-

inder 19' and above the piston 29'. Under this action the unit does not necessarily require a surge tank 44 since the air in the lower portion of the balance cylinder 19' will simply be compressing and expanding on alternate strokes of the piston.

Another method of operation can be produced by closing the valve 60 and opening valve 69 and valve 32. When this is done the auxiliary compressor 50 may be supercharged constantly while the well pumping unit is in normal operation. The device may be operated in this manner with or without employing the surge tank 44. It may also be possible to operate the device by closing valves 60 and 32 and opening valve 56. This will vent the portion of the balance cylinder 19' above the piston 29' and allow the air to pass to the atmosphere. The balance cylinder 19' will then be acting as a simple single-acting compressor being used for the purpose of supercharging the air compressor precisely the same as is accomplished by the structure shown in Fig. 1 of the drawings.

It will thus be seen that the invention embodied in the method and means here shown makes it possible to control a single or double-acting balance cylinder and a main operating compressor as simultaneously actuated by the pumping unit, whereby a desired air pressure may be optionally established and maintained in the counterbalance system by the use of inexpensive and easily operated equipment.

While we have shown the preferred form of our method of pumping air in pumping units and apparatus for carrying out the same, it is to be understood that various changes might be made in the steps of the method as well as the combination, construction and arrangement of the parts of the apparatus by those skilled in the art without departing from the spirit of the invention as claimed.

Having thus described our invention, what we claim and desire to secure by Letters Patent is:

1. In combination with a pump jack having a walking beam; a balance cylinder and piston interposed between said beam and a fixed support whereby air may be compressed within the cylinder as the beam oscillates, a conduit through which said air under pressure may be discharged, a storage tank receiving said air under pressure, an auxiliary air compressor actuated by oscillation of the walking beam, a conduit leading from the auxiliary air compressor to the storage tank, a conduit connecting the balance cylinder and the auxiliary air compressor, and optionally controlled means whereby air under pressure may be delivered from the balance cylinder to the auxiliary air compressor to complete a multi-stage compression of air delivered from the compressor to the storage tank.

2. The structure of claim 1 including a surge tank interposed in the flow line between the balance cylinder and the auxiliary air compressor, whereby air may be delivered under substantially uniform pressure from the balance cylinder to the auxiliary air compressor.

3. The structure of claim 1 including optionally controlled means for delivering air directly to the storage tank from the balance cylinder.

4. In combination with a well pumping jack including a power driven walking beam; a counterbalance unit comprising a balance cylinder and piston interposed between a fixed support and the walking beam, said parts having 75 relative movement as the beam oscillates, an

auxiliary compressor unit including a cylinder and piston and interposed between a fixed support and the walking beam whereby relative movement between said parts may take place as the walking beam oscillates, an air conduit leading to the balance cylinder, an inlet check valve in communication therewith whereby atmospheric air may be drawn into the balance cylinder, a connecting air conduit between said first named conduit and the auxiliary compressor cylinder, a backflow check valve interposed at a point in said conduit, a receiving tank, a discharge flow conduit from the auxiliary compressor to the receiving tank, a backflow check valve interposed at a point therein, and a pipe connection between the connecting conduit and the receiving tank and a backflow check valve therein.

5. The structure of claim 4 including a manually operated cut-off valve interposed in the connecting conduit between the auxiliary compressor and said pipe connection.

6. The structure of claim 4 including a manually operated cut-off valve interposed in the connecting conduit between the auxiliary compressor and said pipe connection, and a surge tank interposed in the connecting conduit at a point between said pipe connection and said manually controlled valve.

7. The structure of claim 4 including a manually operated cut-off valve interposed in the connecting conduit between the auxiliary compressor and said pipe connection, and an atmospheric air inlet connection to the auxiliary compressor cylinder and a backflow check valve therefor.

8. A counterbalance for a well pumping unit having a power actuated walking beam, said counterbalance including a double-acting balancing unit having a cylinder closed at its opposite ends and a piston reciprocating therein, one of said elements being adapted to be secured to the walking beam and the other to a fixed support, an auxiliary compressor including a cylinder and a piston, one of said elements being adapted to be attached to the walking beam and the other element to a fixed support, whereby said balance unit and auxiliary compressor will operate simultaneously, an air receiver, a conduit establishing communication between one end of said balance cylinder and the air receiver, a conduit establishing communication between the auxiliary compressor and the air receiver, atmospheric air inlets to both ends of said balance cylinder, conduits from both ends of said balance cylinder communicating with the auxiliary compressor, and valve means manually operable optionally directing air under compressor from either end of said balance cylinder to said auxiliary compressor.

9. The structure of claim 8 including means for optionally opening either end of said balance cylinder to the atmosphere.

10. The structure of claim 8 including a surge tank interposed between the auxiliary compressor and the conduits leading from both ends of the balance cylinder.

11. A well pumping jack, comprising a power driven walking beam, a pneumatic counterbalance unit associated therewith and comprising a balance cylinder and a piston interposed between a fixed support and the walking beam, said parts having relative movement as the beam oscillates, a conduit through which air may pass to the counterbalance unit, a check valve at a point in said line, an air receiver, a conduit connecting the counterbalance unit and said air receiver,

10 a valve in said line whereby the counterbalance unit may be isolated from the air receiver, a second conduit connected with said counterbalance unit, a valve therein whereby the counterbalance unit may be vented to atmosphere, a conduit connecting with said last named conduit and the air receiver and bypassing the first named valve, a check valve in the conduit carrying the valve which may be open to atmosphere, and a check valve in the bypass conduit permitting the flow of air to the air receiver.

15 12. A counterbalance unit for well pumping jacks including a balance cylinder and piston adapted to be interposed between a fixed support and a walking beam of a pump jack, whereby relative movements between said cylinder and piston may take place as the walking beam oscillates, an auxiliary compressor, a pipeline between the compression chamber of the balance cylinder and said auxiliary compressor, a surge tank interposed at a point in said pipeline, an air receiver, a pipe connection from the portion of the pipeline between the balance cylinder and the surge tank to the air receiver, a check valve interposed in said pipe connection to permit air to flow from the balance cylinder, a check valve interposed in the air receiver connection to permit air to flow into the air receiver, a check valve in the portion of the connecting line from the surge tank to the auxiliary compressor permitting air to flow to the compressor, and a manually operated valve in the same portion of said line to open and close the line.

20 13. In combination with a compressor unit for pump jacks including a balance cylinder and a piston adapted to be interposed between a fixed support and the walking beam of said jack, whereby relative movement may take place between said members as the walking beam oscillates, and an air receiver connected with said balance cylinder; an auxiliary compressor including a cylinder and piston adapted to be interposed between the walking beam and the fixed support to have relative movement as said beam oscillates, a conduit through which fluid may flow from the balance cylinder to the compressor cylinder, a check valve at a point therein, a conduit through which air may flow from the auxiliary compressor to the air receiver, a check valve therein, and a conduit leading from the atmosphere to the auxiliary compressor and a check valve therein, whereby air which has been compressed in the balance cylinder will be delivered to the auxiliary compressor and will be recompressed therein as it is forced into the air receiver.

25 14. The structure of claim 13 including a surge tank in the line of air flow between the balance cylinder and the auxiliary compressor.

30 15. The structure of claim 13 including a conduit directly connecting the balance cylinder with the air receiver, a manually operated valve in said conduit for establishing or interrupting flow therethrough, and a manually operated valve in the conduit connecting the balance cylinder and the auxiliary compressor for establishing and interrupting air therethrough.

35 16. In combination with an air-balanced pump jack having a walking beam, an air counterbalance unit, and an air receiver; an auxiliary air compressor comprising a fixed cylinder, a piston adapted to be connected to the walking beam and reciprocating within said fixed cylinder as the walking beam of the pump jack oscillates whereby air will be compressed in the fixed cylinder, an intake pipe establishing communication

between the air-balanced pump jack and the auxiliary compressor cylinder, a check valve at a point along said intake pipe, a communicating pipe between the auxiliary compressor cylinder and an air receiver of the counterbalance unit, a check valve at a point along the connecting pipe, an air pipe establishing communication between said auxiliary compressor cylinder and the atmosphere, and a check valve therein.

17. In combination with a counterbalance cylinder, a piston and air receiver of an air counterbalance pump jack, an auxiliary compressor unit comprising a piston and fixed cylinder adapted to have relative movement to each other as the walking beam of the pump jack oscillates, a conduit connecting the air receiver and the air counterbalance cylinder, a manually operated cut-off valve therein, a conduit connecting the counterbalance cylinder and the cylinder of the auxiliary compressor, a manually operated cut-off valve therein, a bypass conduit, a check valve

5

in said connecting conduit, and a manually operable valve in the connecting conduit between the point of connection of the bypass conduit and the auxiliary air compressor, a conduit connecting the auxiliary air compressor with the air receiver, and a check valve therein.
